UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed May 29, 1923. Serial No. 642,236.

To all whom it may concern:

Be it known that I, EDWIN E. BARNEY, citizen of the United States, and resident of New Rochelle, in the county of Westchester and State of New York, have invented certain new and useful Improvements in Type-writing Machines, of which the following is a specification.

My invention relates to typewriting machines, and more particularly to a small, compact, portable machine intended to be transported or carried in its carrying case, such a machine, for example, as the Remington Portable.

In portable machines it is desirable to confine the length of the platen as much as possible, consistent with the requirement for writing on paper of standard widths, and to accordingly confine the length of the carriage in order not to exceed the necessary widthwise dimensions of the machine. One difficulty, however, that presents itself in thus restricting the machine to taking paper of approximately standard widths, is that work sheets of greater widths, and more particularly standard large sized envelopes, cannot be introduced into the machine without folding them, which is undesirable.

One object of my invention is to provide a construction which overcomes this difficulty and enables comparatively wide work sheets, or standard large sized envelopes, to be introduced in unfolded condition into and be properly fed through the machine, and in which it is unnecessary to increase the length of the platen or the carriage, to attain the results.

Another object of my invention is to provide a novel construction and arrangement of parts, including a finger piece for turning the platen which may be moved from an expanded position for use to a compact position where it enables the machine to be enclosed within its carrying case.

In the accompanying drawings, wherein like reference characters indicate corresponding parts in the different views,

Figure 1 is a detail fragmentary rear elevation, with parts in section and parts omitted, of a Remington Portable machine embodying my invention and conditioned for transportation within its carrying case.

Figure 2 is a detail fragmentary rear view, with parts in section, of the platen and the means for supporting it at the right-

hand end; the finger wheel being shown in its expanded position for use.

Figure 3 is a fragmentary end view with parts broken away, of the carriage and some of the associated parts as seen from the right.

Figure 4 is a detail fragmentary front elevation, with parts in section, of the right-hand end portion of the carriage and some of the associated parts.

Figure 5 is an end view of the carriage and associated parts as seen from the left, and with parts in section.

Figure 6 is a detail perspective view of the right-hand combined carriage end plate and off-set bracket arm.

I have shown my invention in the present instance embodied in a Remington Portable machine, but have illustrated only so much of said machine as is necessary to disclose my invention in its inclusion therein. The invention may be readily employed in such a machine without material modification of its existing structural features except by the substitution of parts, as will hereinafter more clearly appear. It should be understood, however, that the invention is not restricted to its employment in such machines.

The present invention has the same general ends in view as the construction disclosed in a companion application filed by me of even date herewith and bearing Sr. No. 642,235. In said companion application claims are included which cover the construction disclosed herein, whereas the claims of the present application are specific to features not disclosed in said companion application.

In the Remington Portable machine, as at present marketed, and as disclosed in the application of Joseph B. Holden, Sr. No. 533,945, filed Feb. 3, 1922, a plate $8\frac{1}{2}$ inches long is employed, which enables a full written line to be produced on standard sized sheets; such sheets not exceeding $8\frac{1}{2}$ inches in width. However, said machines do not enable a large sized standard envelope of $9\frac{1}{2}$ inches to be used in the machine without folding such envelope. By my present invention, a work sheet or envelope of $9\frac{1}{2}$ inches in width may be used without folding it, and without increasing the length of the platen or carriage, so that the machine may be received within the same carrying case that is now in use, and without eliminating

any of the advantages which accrue to the said machine as it is now employed.

In the Remington Portable machine, a carriage support 8 is mounted at its rear end for fore-and-aft case shifting movement on parallel arms 9. These arms are fixed on a rock shaft 10, pivoted at its reduced ends 11 in the frame 12 of the machine. The upper ends of the arms 9 are pivoted at 13 to lugs 14 on the carriage support. The shiftable support 8 carries a carriage comprising a main carriage bed 15 mounted in the usual manner on bearing rollers (including rollers 16) to travel along the support 8. The carriage and associated parts remain substantially as they formerly were except at the right-hand end of the carriage. At this end the usual carriage end plate has substituted therefor a member, preferably formed as a combined end plate and bracket arm. This member is designated as a whole by the reference numeral 17, and is shown detached and in detail in Fig. 6. The member 17 is preferably made of sheet metal and comprises a foot piece 18 secured by screws 19 to the carriage bed 15. Projecting upwardly from this foot piece is a carriage end plate 20, preferably formed as shown, with all parts thereof arranged outside of lines coincident with the cylindrical surface of the platen. This is in order that the end plate will not extend into the path of a work sheet *a* that may overlap the right-hand end of the platen, as will be understood from a consideration of Figs. 3 and 4. Projecting outwardly and horizontally from the foot piece 18 a considerable distance beyond the end plate 20, and beyond the right-hand end 15^a of the carriage bed, and the corresponding end of the paper apron 21 is a bracket arm 22. Extending upwardly from the arm 22 is an arm 23 that terminates before it reaches lines coincident with the cylindrical surface of the platen, in order not to form an obstruction for the overlapping end of a work sheet *a*, as indicated in Fig. 4. Bent to the right from the upper end of the arm 23 is a substantially horizontally disposed arm 24 over which an overlapping end of the work sheet *a* is adapted to lie, as shown in Fig. 4. Projecting upwardly from the outer end of the arm 24 is an upright arm 25 that extends to the pivotal axis of the platen 26 and is provided with a bearing 27 by which the platen is supported at one end thereof. A hollow cup-shaped finger piece or wheel, designated as a whole by the reference numeral 28, is preferably formed from metal as a shell having an outer disk-like head 29 from the edge of which extends a cylindrical flange 30 that projects towards the platen. The head 29 is formed with a tubular hub 31 that extends through and is supported in the bearing 27 on the supporting bracket. A spindle 32 has its outer end seated in the hub 31 and is secured thereto by a screw 33 threaded into a tapped opening in the hub and extending into a transverse opening 34 in the spindle. Said spindle receives a bearing in a central opening 70 in a platen head 35 secured by screws 36 to the wooden core 37 of the platen. The right-hand portion of the spindle 32 has a longitudinally extending spline groove 38 therein, and a spline projection 39 in the 75 central bearing opening in the platen head extends into said groove. The spindle is thus connected to turn with the platen but may receive an independent longitudinal movement therein. The outward longitudinal 80 movement of the spindle is limited by a pin 40 secured to the spindle and projecting into the spline groove 38. When the spindle is moved out to the Fig. 2 position, the pin 40 strikes the spline projection 39 85 and prevents a further outward movement of the spindle. I prefer to employ a sleeve 41 which surrounds the hub 31 and that part of the spindle 32 which projects outside of the platen. It will be seen that the right- 90 hand end of the sleeve bears against the bearing member 27 on the bracket, whereas the platen head 35 bears against the left-hand of the sleeve. The sleeve, therefore, receives the end thrust of the platen to the 95 right and holds it against movement in this direction. In order that access may be gained to the screw 33, I provide an opening 42 in one side of the sleeve 41 and through which the screw may be introduced or withdrawn. 100

The construction described enables the finger wheel to be moved from its expanded position for use shown in Figs. 2 and 4, and in dotted lines in Fig. 1, to a compact position indicated in full lines in Fig. 1. It will be seen that the construction and relation of the parts are such that when the finger wheel is in the expanded position, said wheel in the main is outside of or beyond 105 the bracket arm 25 and the bearing member 27 carried thereby. It will be seen, moreover from an inspection of Fig. 1 that in this position the finger wheel extends into the path of the right-hand side 43 of the cover 110 of the carrying case and prevents said case from being closed to enclose the machine therein. When, however, the finger wheel 28 is moved from the expanded to the full line position in Fig. 1, said wheel telescopes over 115 the bracket arms 24 and 25 and over the bearing 27; such parts at this time being received within the hollow wheel, and the wheel in the main will extend to the left of the bracket arm 25. The step-shaped arrangement of the bracket arms 22, 23, 24 and 25 enables an efficient support to be provided for the platen at this end thereof without interfering with the overlapping work sheet *a* extending over the bracket arms 22, 23 and 120 125 130

24 to the inner face of the bracket arm 25 when the finger wheel is in position for use. The construction also enables the finger wheel to receive a telescoping movement over 5 the arms 24, 25 and the bearing 27, as described, so that said parts may be received within the wheel and not interfere with its movement to compact position, thereby enabling the cover of the carrying case to be 10 closed.

It will be seen that the diameter of the finger wheel 28 is greater than that of the platen, and that when the wheel is in the expanded position the inner edge 44 (see Figs. 15 3 and 4) of the wheel will be in substantial alignment with or inside the inner face of the bracket arm 25, and in a position to act as a side edge gage for the work sheet *a*, to facilitate the introduction of the sheet into 20 the machine and to indicate the limit to the right beyond which the operator cannot carry the sheet.

The left-hand end of the spindle 32 is received and adapted to move longitudinally 25 and to turn in a bearing member 45 in the left-hand end plate 46 of the carriage, in the usual manner. As is usual in the Remington Portable machine, and as is disclosed in the application of Joseph B. Holden, 30 Sr. No. 547,128, filed March 27, 1922, a member 47 is pivoted at 48 on the left-hand end plate of the carriage. This member 47 is provided with a locking finger 49 that is received in a transverse slot 50 35 in the bearing member 45, and is adapted to extend across the bearing opening therein, as shown in Fig. 5. The member 47 is also provided with a depending locking member or projection 51 adapted to be received in a 40 recess 52, see Fig. 1, of a spring locking latch 53 secured at one end to the carriage support 8. In the present instance this locking latch is secured to the carriage about $\frac{1}{16}$ of an inch further to the left than ordinarily. The member 47 also has an arm 54 45 which carries a laterally bent finger piece 55 located in the rear of the carriage releasing arm 56 which terminates in a finger piece 57. This arm 56 is connected to a supporting plate 58 mounted on the carriage by pivots 59 and carrying a feed rack 60 which normally engages the lowermost feed dog 61 to restrain the power driven carriage against 50 movement in the direction of its feed.

55 It will be understood that the finger 49 normally extends into the path of the left-hand end of the spindle 32, as shown in Fig. 5, and prevents a longitudinal displacement of the spindle to the left. This 60 prevents the finger wheel from being moved to the left where it may clear the side wall 43 of the cover of the carrying case. Therefore in this condition the cover is prevented from being closed, as hereinbefore pointed 65 out.

In order to condition the machine for enclosure within its carrying case, the operator, aside from contracting the type bars in the usual manner, presses forward on the finger piece 55 and then moves the finger 70 wheel 28 to the left to the limit of its movement. The effect of actuating the finger piece 55 is to move the locking finger 49 out of the path of the spindle 32, move the locking projection 51 down into effective position, 75 and move the carriage releasing arm 56 forward, thereby releasing the feed rack 60 to free the carriage. While the parts are thus maintained by pressure exerted by the operator on the finger piece 55, the finger 80 wheel 28 is moved to the full line Fig. 1 position, as explained. This thrusts the left-hand end portion of the spindle 32 into the path of the finger 49 and prevents a return movement of the member 47 to normal position 85 under the action of its spring 62. This results in locking the projection 51 in effective position and in locking the feed rack out of engagement with the normally engaged feed dog. The carriage is then moved from 90 its off centered position in either direction to a substantially centered position in its line of travel. When a substantially centered position is reached, the members 51 and 53 of the center lock automatically co-act to 95 lock the carriage against travel in either direction from said centered position. With the machine thus conditioned, the cover may be closed and the machine enclosed within 100 its carrying case.

To re-condition the machine for use, it is merely necessary after removing the cover, to expand the type bars in the usual manner, and then move the finger wheel 28 from the full to the dotted line position in Fig. 1. The effect of this is to withdraw the left-hand end portion of the spindle 32 out of the path of the locking finger 49. The spring 62 will then return the member 47 to normal position shown in Fig. 5, thereby 105 rendering the center lock ineffective and returning the carriage to the restraint of its escapement mechanism, by permitting the feed rack to return to normal position under the action of its springs 63.

110 While I prefer to employ the finger wheel 28 in combination with the other features disclosed to control the center lock and carriage release, yet from certain aspects of my invention it is immaterial whether the feed wheel be employed in such a combination.

115 It will be understood that in the specific construction as disclosed in the present instance, when a $9\frac{1}{2}$ inch envelope or work sheet *a* is in the machine and overlaps the right-hand end of the platen to the capacity of the machine, as shown in Fig. 4, the finger wheel is in position for use and 120 extends outside of the supporting arm 25 125 130

and beyond the range of the envelope or work sheet, where the finger wheel may be used effectively without interference from or interference with the envelope or work sheet.

Various changes may be made in the construction shown and described, and parts thereof may be employed without others without departing from my invention as it 10 is defined in the accompanying claims.

What I claim as new and desire to secure by Letters Patent is:—

1. In a typewriting machine, the combination of a carriage, a platen carried thereby, a bearing member which supports the platen at one end, and a hollow finger wheel connected to turn the platen and movable longitudinally thereof from an expanded position for use to a compact position, said 20 finger wheel in moving to compact position telescoping over and receiving said bearing member therein.

2. In a typewriting machine, the combination of a carriage, a platen carried thereby, a bracket that projects outwardly beyond one end of the carriage and has a supporting arm which supports one end of the platen, a hollow finger wheel connected to turn the platen and movable longitudinally 30 thereof from an expanded position for use to a compact position, said finger wheel in moving to compact position telescoping over and receiving said bracket arm therein.

3. In a typewriting machine, the combination of a carriage, a platen carried thereby, a finger wheel of larger diameter than the platen, and means which enable said finger wheel to coact with a side edge of a work sheet and act as a side edge gage for a 40 sheet as it is introduced into the machine.

4. In a typewriting machine, the combination of a carriage, a platen carried thereby, a finger wheel of larger diameter than the platen, and means which enable said 45 finger wheel to coact with a side edge of a work sheet and act as a side edge gage for a sheet as it is introduced into the machine, said means including means that enable said finger wheel to be moved from a compact 50 position to an expanded position for use.

5. In a typewriting machine, the combination of a carriage, a platen carried thereby, a bracket that projects outwardly beyond one end of the carriage and has a 55 double step-shaped bend therein and terminates near the axis of the platen where it supports the platen and is formed with an intermediate substantially horizontally disposed portion over which a work sheet that 60 projects beyond the adjacent end of the platen may extend, and a finger wheel for the platen arranged outside of said bracket.

6. In a typewriting machine, the combination of a carriage, a platen carried thereby, a bracket that projects outwardly be-

yond one end of the carriage and has a double step-shaped bend therein and terminates near the axis of the platen where it supports the platen and is formed with an intermediate substantially horizontally disposed portion over which a work sheet that 70 projects beyond the adjacent end of the platen may extend, and a hollow finger wheel connected to turn the platen and to be shifted longitudinally thereof from an 75 expanded position for use to a contracted position, the finger wheel in moving to contracted position telescoping over the platen supporting end of the bracket and over said horizontally substantially disposed portion 80 thereof.

7. In a typewriting machine, the combination of a carriage, a platen, a bearing member for supporting the platen at one end on the carriage, and a cup-shaped finger 85 wheel for turning the platen and in which the said bearing is received.

8. In a typewriting machine, the combination of a carriage, a platen, a bearing member for supporting the platen at one 90 end on the carriage, a cup-shaped finger wheel for turning the platen and in which the said bearing is received when the wheel is in compact position, a spindle on which said finger is mounted, and means for connecting said spindle to turn with the platen but permitting the spindle to be shifted 95 longitudinally of the platen and enable the finger wheel to be shifted outwardly from said compact position.

9. In a typewriting machine, the combination of a platen, a bearing member for supporting the platen at one end on the carriage, a cup-shaped finger wheel for turning the platen and in which the said bearing 105 is received when the wheel is in compact position, a spindle on which said finger is mounted, means for connecting said spindle to turn with the platen but permitting the spindle to be shifted longitudinally of the 110 platen and enable the finger wheel to be shifted outwardly from said compact position, and a spacing sleeve surrounding said spindle and interposed between one end of the platen and said bearing and receiving 115 the end thrust of the platen in one direction.

10. In a typewriting machine, the combination of a carriage, a platen, a bearing member for supporting the platen at one end on the carriage, a cup-shaped finger wheel 120 for turning the platen and in which the said bearing is received when the wheel is in compact position, a spindle having a splined connection with the platen, a connecting screw for connecting said finger wheel to 125 the spindle, and a spacing sleeve surrounding said spindle and interposed between one end of the platen and said bearing to receive an end thrust of the platen and prevent an axial movement thereof in one direction. 130

- said sleeve having an opening in a side thereof through which access may be gained to said screw which connects the finger wheel and spindle.
- 5 11. In a typewriting machine, the combination of a carriage, a bracket secured to the carriage and extending outwardly for a considerable distance beyond one end thereof and provided with a bearing, a 10 platen, a spindle connected to turn with the platen and passing through said bearing, and a hollow finger wheel connected to said spindle and surrounding said bearing in the bracket arm.
- 15 12. In a typewriting machine, the combination of a carriage, a bracket secured to the carriage and extending outwardly for a considerable distance beyond one end thereof and provided with a bearing, a 20 platen, a spindle connected to turn with the platen and to be shifted longitudinally thereof, said spindle passing through said bearing, and a cup-shaped finger wheel connected to said spindle and shiftable there- 25 with longitudinally of the platen from a compact to an expanded position for use, the finger wheel when in the compact position surrounding said bearing.
13. In a typewriting machine, the combination of a carriage, a platen, a bearing member for supporting the platen at one end on the carriage, a cup-shaped finger wheel for turning the platen and in which the said bearing is received, escapement 30 mechanism for the carriage, and means controlled by the finger wheel when it is in compact position for locking the carriage free from the restraint of its escapement mechanism.
- 35 14. In a typewriting machine, the combination of a carriage, a platen, a bearing member for supporting the platen at one end on the carriage, a cup-shaped finger wheel for turning the platen and in which the said bearing is received, a center lock 40 for locking the carriage substantially centered in its line of travel, and means controlled by said finger wheel for maintaining the center lock in effective condition when 45 said finger wheel is in the compact position.
15. In a typewriting machine, the combination of a carriage, a platen, a bearing member for supporting the platen at one end on the carriage, a cup-shaped finger wheel for turning the platen and in which 50 said bearing is received, escapement mechanism for the carriage, means controlled by the finger wheel when it is in compact position for locking the carriage free from the restraint of its escapement mechanism, a center lock for locking the carriage substantially centered in its line of travel, and means controlled by said finger wheel for maintaining the center lock in effective condition when 55 said finger wheel is in the compact position.
16. In a typewriting machine, the combination of a platen, a bearing member for supporting the platen at one end, a hollow finger wheel that receives said bearing member, said finger wheel having a hub that receives a support in said bearing member, and a connection between said hub and the platen and by which the platen is supported at one end through said hub and the bearing 60 member that supports it.
17. In a typewriting machine, the combination of a platen, a bearing member for supporting the platen at one end, a hollow finger wheel that receives said bearing member, said finger wheel having a hub that receives a support in said bearing member, and a connection between said hub and the platen that enables the finger wheel to be moved outwardly longitudinally of the 65 platen from the position where it surrounds said bearing to an expanded position for use, said connection constituting means by which the platen is supported at one end through said hub and the bearing member 70 that supports it.
- Signed at the borough of Manhattan, city of New York, in the county of New York and State of New York, this 28th day of May, A. D. 1923.
